UNITED STATES PATENT OFFICE.

GEORGE E. KELLER AND JESSE F. PENDER, OF VANCOUVER, WASHINGTON.

SEPARATOR.

1,249,635.

Specification of Letters Patent.

Patented Dec. 11, 1917.

Application filed April 26, 1917. Serial No. 164,802.

To all whom it may concern:

Be it known that we, GEORGE E. KELLER and JESSE F. PENDER, citizens of the United States, residing at Vancouver, county of Clark, State of Washington, have jointly invented certain new and useful Improvements in Separators, of which the following is a specification.

Our invention relates to separators in general, and particularly to that class of separators known as hydraulic, and used especially in mining to separate various grades of ore.

The objects of our invention are to produce a device of extreme simplicity; to produce a device of minimum weight for the use of prospectors; and to produce a device of economical construction and use.

We accomplish the above objects, and other desirable results, by means of the construction illustrated in the accompanying drawing, like characters of reference indicating like parts throughout the several views, and in which:

25 Figure 1 is an axial sectional elevation of our device.

Fig. 2 is a detail fragmentary view of a portion of the ore feed pipe.

The device is inclosed by an outer casing 3, preferably made of glass, and having at the lower end thereof a head of inverted truncated conical shape, and at the upper end thereof a head 5, substantially disk shaped.

35 The casing is clamped between said heads by bolt rods 6, and a water tight joint is effected between the casing and the heads by gaskets 7 of rubber or other suitable material.

40 The lower head 4 is provided with a clean-out cap 8 and a drain pipe 9.

Legs 10 attached to head 4 support the device.

45 Centrally attached to head 5 is an inner casing 11, made preferably of glass, and having upon the lower end thereof an annular flange 12.

Said casing 11 is clamped between head 5 and flange 12 by bolt rods 13, and a water tight joint is effected between casing 11 and head 5 by means of a gasket 14 of rubber or other suitable material.

50 Centrally mounted upon head 5, and above the same, is a pipe 15, having an out-

let pipe 16 attached thereto, said pipe 15 being in communication with casing 11.

Water supply pipes 17 enter the head 5 in the annular space intermediate the casing 3 and the casing 11.

An ore supply pipe 18 is disposed within pipe 15 and casing 11, the upper end thereof being connected to a suitable funnel 19, or the like, which closes the upper end of pipe 15.

The water introduced through pipes 17 flows downward intermediate casings 3 and 11, upward through casing 11 and pipe 15, and is discharged from pipe 16, as illustrated by the full line arrows.

The ore, or other material to be separated, is introduced into casing 11 by means of pipe 18 and funnel 19, and there encounters the rising current of water within casing 11.

The intensity of the upward current within casing 11 is regulated so that it is just sufficient to float the lighter particles of the material being separated, but will allow the heavier particles to settle against the current into head 4.

In order to facilitate the separation of the particles under the action of the water current we find it desirable to discharge the material from pipe 18 in an annular ring of radially projected jets.

This we accomplish by terminating the pipe 18 some distance above the lower end of casing 11, and suspending therefrom a pipe 20 by means of straps 21.

The upper end of pipe 20 adjacent pipe 18 is closed, as shown in Fig. 2, and spaces 22 are left between adjacent straps 21.

The material to be separated is discharged from said spaces in substantially a radial manner, and subjected to the action of the ascending current of water, which carries upward the lighter particles as shown by the full line arrows, and allows the heavier particles to sink into head 4 as shown by the dotted arrows, whence they may be withdrawn by removing the clean-out cap 8.

Our invention may be made of any size and constructed of any material deemed convenient and suitable for a device of this character, and while we have illustrated and described a form of construction and arrangement of parts found desirable in materializing our invention, we wish to include

in this application for Letters Patent all mechanical equivalents and substitutes that may fairly be considered to come within the scope and purview of our invention as defined in the appended claim.

Having disclosed our invention so that others skilled in the art may be enabled to construct and to use the same what we claim as new and desire to secure by Letters 10 Patent is:

A separator comprising a reservoir; a downwardly projecting conical head upon the lower end of said reservoir; a head upon the upper end of said reservoir; a tube secured to said head and projecting downward therefrom within said reservoir and substantially coaxial therewith; a pipe se- 15

cured to said head and projecting upward therefrom and being in connection with said tube; an overflow from said pipe; a feed 20 pipe within said pipe and projecting downward within said tube substantially coaxial therewith and having adjacent the lower end thereof a plurality of discharge slots; a feed hopper closing the upper end of said pipe and connecting with said feed pipe; and supply pipes entering said reservoir through said upper head thereof.

In witness whereof we claim the above as our own we hereunto set our hands, at 25 Portland, county of Multnomah, State of Oregon, this 3d day of April, 1917.

GEORGE E. KELLER.
JESSE F. PENDER.
